UNITED STATES PATENT OFFICE.

HERBERT L. BROWN, OF CINCINNATI, OHIO, ASSIGNOR TO THE H. L. BROWN FENCE AND MANUFACTURING COMPANY, OF CINCINNATI, OHIO.

DESIGN FOR A WIRE FENCE.

42,433.

Specification for Design.

Patented Apr. 30, 1912.

Application filed January 9, 1912. Serial No. 670,302. Term of patent 14 years.

To all whom it may concern:

Be it known that I, HERBERT L. BROWN, a citizen of the United States, residing at Cincinnati, in the county of Hamilton and State of Ohio, have invented a new, original, and ornamental Design for Wire Fences, of which the following is a specification, reference being had therein to the accompanying drawing, which is a side view of my new, original, and ornamental design for wire fences.

This design consists essentially of the top bow portions A; the vertical stem portions B, which extend to the bottom of the fence; the intermediate bow portions C, which have their stems D extending to the bottom of the fence and the straight stems or wire pick-

ets E inclosed by the bow portions C. The stems of the bow portions described and also the short wire pickets E are united by longitudinally extending wires G, H, I, J, K, L and M, the whole constituting the new, original and ornamental design for wire fences shown in the said accompanying drawing.

I claim—

The ornamental design for a wire fence, as shown and described.

In testimony whereof, I hereunto affix my signature in the presence of two witnesses.

HERBERT L. BROWN.

Witnesses:

R. S. OPPENHEIMER,
PAUL V. CONNOLY.
